Primary Examiner — George D. Kirschbaum*Assistant Examiner* — Jennifer Watkins(74) *Attorney, Agent, or Firm* — Workman Nydegger(57) **CLAIM**

The ornamental design for a knee brace, as shown and described.

DESCRIPTION

FIG. 1 is a first side elevational view of a knee brace, showing our design.

FIG. 2 is a front elevational view of the knee brace of FIG. 1.

FIG. 3 is a rear elevational view of the knee brace of FIG. 1.

FIG. 4 is a second side elevational view of the knee brace of FIG. 1.

FIG. 5 is a top view of the knee brace of FIG. 1; and,

FIG. 6 is a bottom view of the knee brace of FIG. 1. The broken lines are included for the purpose of illustrating environmental structure and form no part of the claimed design.
